UNITED STATES PATENT OFFICE

158,997

COFFEE POT

Royce L. Parker, Addison, Ill.

Application January 2, 1948, Serial No. 143,490

Term of patent 3½ years

(Cl. D44—26)

To all whom it may concern:

Be it known that I, Royce L. Parker, a citizen of the United States, residing at Addison, county of Du Page, and State of Illinois, have invented a new, original, and ornamental Design for Coffee Pot, of which the following is a specification, reference being had to the accompanying drawing, forming a part thereof, in which:

Figure 1 is a perspective view of a coffee pot, showing my new design; Fig. 2, a top plan view; and Fig. 3, a side view in elevation.

I claim:

The ornamental design for a coffee pot, as shown.

ROYCE L. PARKER.
